ANNOUNCING APPARATUS

Hazard E. Reeves, New York, N. Y.

Application July 29, 1941, Serial No. 404,574

17 Claims. (Cl. 179—100.3)

This invention relates to new and useful improvements in announcing systems and has particular although not necessarily exclusive relation to a time controlled announcing system.

The objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:

Fig. 1 is a plan view showing an announcing apparatus constructed in accordance with the invention;

Fig. 2 is a side elevational view of the apparatus;

Fig. 3 is a rear elevational view taken as looking from the right in Fig. 2;

Fig. 4 is a side elevational view of the lens system employed;

Fig. 5 is a longitudinal sectional view taken as along the line 5—5 of Fig. 4;

Fig. 6 is a transverse sectional view taken as along line 6—6 of Fig. 4;

Fig. 7 shows the wiring diagram;

Fig. 8 is a detail view showing a slight modification of the switching means employed; and

Fig. 9 shows a modified wiring diagram.

Fig. 10 is a view of the apparatus adapted to a plurality of film rolls.

Referring in detail to the drawings the present apparatus is shown as mounted on a casting generally designated 10 and which includes a bottom or plate-like portion 11 provided intermediate its ends with a bearing member 12 receiving the lower end of a shaft 13. A drum 14 is rotatably mounted by the shaft 13 and forms a film support as will later more fully appear. An electric motor 15 is supported at the upper side of plate-like portion 11 as upon a plate 16 in turn supported by posts 17 on the base.

This motor is equipped with suitable reduction gearing (not shown) and drives a vertical shaft 18 to which is secured a plate 19 having a tapered upper side on which is a block 20. At the under side of the plate 19 and fastened to the plate or directly to the shaft 18 is a pulley 21. A belt 22 trained over said pulley passes about the drum 14 as shown, whereby the motor 15 serves to rotate the plate 19, the central block

20 on the upper side of said plate and the drum 14.

An idler pulley 23 is supported by an arm 24 on the upper end of a post 25 received in a part 26 of the casting 10. A thumb screw 27 secures the post 25 in the desired position of vertical adjustment. A coil spring 28 has one end secured to the post 25 as at 29 and its other end 30 is connected with the arm 24 constantly tending to swing the same and thus maintaining the idler 23 against the belt 22. On turning of the bar 25 in the socket 26 and thereafter tightening the thumb screw 27 the tension at which the coil spring 28 forces the idler 23 against the belt may be increased or decreased.

A roll of film 31 is disposed on the tapered upper side of the disc 19 and about the block 20. This roll of film has a hollow center and is disposed about the block 20 and the film is fed from the center of the roll about the drum 14 and back to the outer side of the roll, it being understood that the film is endless. The surface on which the film rests being tapered as shown there is a tendency of the film to open whereby it is easily and smoothly fed from its center. Due to the fact that the film is fed from a smaller diameter than that on which it is rewound it must be handled in such manner as to permit of a certain slippage and this is provided for by the 25 tapering of the surface of disc 19. In Fig. 1 the lead from the center of the roll is shown at 32 and the film is carried outwardly about a guide pulley 33 and then rearwardly at 34 and over and between guide rollers 35 and 36, the latter serving to hold the film against the drum as at 37.

At 38 where the belt 22 comes into driving relation with the drum 14 such belt lies over a portion of the film and the upper portion of the film (designated 39 in Fig. 2) projects above the drum 14. The action of the belt 22 holds the film against the drum so that the film moves steadily and accurately with the drum. At the other side of the drum the film leaves the same and this portion of the film is designated 40 in Fig. 1 and it passes over a tapered guide roll 41 and back to the outer side of roll 31.

As the film leaves the center of roll 31 it passes over a guide pulley 42 supported by an arm 43 and such guide pulley may be adjusted along the arm 43 to the extent of the slot 44 in said arm. Associated with the guide pulleys 33 and 42 are rollers 33a and 42a respectively serving to maintain the film in proper relation to the pulleys. Arm 43 is pivotally mounted on an arm 45 as through the use of a thumb screw 46 whereby

pivotal adjustments may be made and the arm 45 is in turn supported on a post 47 mounted in a socket 48 formed as part of the casting 10. A thumb screw 49 provides a means for securing the post 47 in the desired position of vertical adjustment.

On the outer portion of the arm 45 is a guide roller 50 adjustable along the arm as provided for by the slot 51 and such roller is against the other side of the film roll 31 so as to keep the latter confined. The pulley 33 above referred to is supported on the outer end of an arm 52 which latter is carried by the upper end of a post 53 supported from a socket member 54 comprising part of the casting 10. A thumb screw 55 provides means for securing post 53 in an adjusted position.

Supported intermediately of the arm 52 is an arm 56 adjustably secured in place as by a thumb screw 57 and supporting a roller 58 also bearing against the outer side of the film roll 31. A flat arm 59 is secured on the arm 56 as by means including a wing nut 60 and such flat arm serves to hold the film roll against stacking. Guide rolls 35 and 36 above referred to are supported by an arm 61 secured to the upper end of a post 62 having its lower end disposed at a socket 63 comprising a part of casting 10. A thumb screw 64 secures the post 62 in the desired position of vertical adjustment.

The parts above described are located at one side of the drum 14 and comprises the means for rotating the drum and feeding the film to and about the same. The control and reproducing means of the announcer are shown as generally located at the other side of the drum. Supported by a step-like portion 65 of the casting 10 is a light source 66 substantially enclosed by a hood 67 having an opening 68 in the front wall thereof. At 66a is shown an arm engaging the center contact of lamp 66.

Actually the casting portion 65 is split as at 68 and a screw 69 is used to draw these split portions toward one another to clamp the base or socket of the light source 66. The hood 67 may be secured in a desired manner and as here shown is releasably secured in place by spring clips 70. A tubular device 71 containing the lens system is clamped in place by the tightening of a screw 72 passing through the bifurcated portions of the portion 73 of the casting and it is noted (see Fig. 2) that one end of the device 71 aligns with the hood opening 68 while the other end aligns with the upper portion 39 of the film.

A rotatably adjustable bracket 74 clampingly receives a photo-electric cell 75 the socket of which is shown at 76. On loosening of the screw 77 the cell may be removed by replacement and upon loosening of the thumb screw 78 the bracket 74 may be adjusted on the support 74a to adjust the photo-electric cell. The lens system disclosed comprises a bar-like structure 79 having a small opening 80 there through and at one end cut out as at 82. Into such end is entered the reduced portion of a plug or end 83 having an opening 84 aligning with the opening 80.

At the respective ends of the opening portions 80 and 84 pieces 85 and 86 of a glass rod are disposed and such pieces traverse the mentioned openings and are secured in place in any desired manner. In the socket portion 82 of the part 79 a pair of plates 87 and 88 are secured as by small screws 89 and these plates are substan-

tially half discs and have their flat edges spaced as desired to provide the desired slot for the passage of light.

Any time control device 90 is mounted on the base or casting 10 and includes an arm 91 which is continually rotated as about the center 92. In Fig. 1 the arm 91 is shown as engaging the switch 93 and maintaining it closed and as about to engage the switch 94 to close it. A third switch 95 is provided with the roller 96 which rolls against the film on the drum 14. Such film at the desired spaced intervals is provided with notches and as such notches pass the roller 96 the latter engages the drum and grounds the circuit stopping the apparatus. The apparatus includes the transformer 97, amplifier tubes 98, tone and volume controls 99 and 100, and condensers 101, which latter serve to eliminate electrical interference from certain switches employed as will be described.

The circuit of the device is shown in Fig. 7 and at 102 are the connections preferably to a 110 volt alternating current source. In said circuit are the amplifier and motor switches 93 and 94. The amplifier is generally designated 114 and has the transformer 97 associated therewith. A pair of relays 104 and 105 have normally closed switch means 106 and 107 associated therewith and of which the movable elements 108 and 109 comprise the armatures of the relays.

In Fig. 7 the drum 14 is grounded at 110, the transformer at 112 and the light source 66 at 113. The switches 93 and 94 are normally open and in the operation of the device are only momentarily closed as by the arm 91 of the time controlled device 90 although it will be apparent that such switches may be closed manually if desired. Preferably the device 90, when employed, is a synchronous motor driven device and in such instance may be connected with the terminals 102 so as to be constantly operating when the device is connected.

Initially the arm 91 engages the switch 93 closing the same to have the amplifier "heat up" to be ready for use. Thereafter the arm 91 momentarily closes the switch 94 and this shorts out the relay 104 permitting the armature 108 to rise and make contact closing switch 106. When the switch 94 shorts out the relay 104 the motor is driven and feeds the film as above set forth. At this time, the circuit is closed through the motor since switches 106 and 107 are both closed. The machine operates and makes any desired announcement as may be recorded on the film; and then one of the notches 116 in the film comes opposite the roller 96 and the same engages the drum closing the circuit through the drum from the transformer and energizing the relay 105.

When this occurs the armature 109 of switch 107 is drawn downwardly breaking the motor circuit as the switch 94 is now open and the current passing through coil 104 energizes it to attract armature 108 opening switch 106. Instantly the switch 107 opens, the relay 104 is again energized and opens switch 106 by attracting its armature 108; and the switch 94 was already open. Relay 104 no longer being shorted out of the circuit motor 15 is not functioning. By momentum the drum moves sufficient to carry any particular notch 116 beyond the roller 96 so that such roller only momentarily closes the circuit through relay 105, and when the machine comes to a stop the roller is again engaging the

film and is insulated from the drum. As the motor begins to drive the film roll 31 is rotated so that film is fed from the center of the roll and the film forms a loose spiral as shown adjacent the idler 42 and the film is fed from the spiral and trained about the drum 14. Belt 22 being driven and being disposed over a part of that portion of the film which is on the drum serves to rotate the drum and to hold the film in fixed relation therewith.

The sound track is in the upper exposed portion of the film, designated 39 in Fig. 2, and the light from the source 66 (reduced to a narrow vertical beam by the lens system 71) is directed through this portion of the film to the cell 75. Such cell through the leads 115 is connected with the amplifier 114. Any message or the like on the film is thus transcribed and amplified and broadcast.

At desired intervals the film is provided with the notches 116 and when one of these notches comes opposite the roll 96 the latter engages directly the metal drum 14 grounding the circuit and stopping the device. Attention is directed to the fact that the various guide rolls have reduced diameter portions 117 adjacent their upper ends and this construction is used since the recorded portion will not then come into engagement with any portions of such guide rollers.

The announcer system of the invention may be made up to use as an advertising device or as a device for giving warnings or the like. For example, the film has recorded thereon time intervals concerning each hour or part thereof of the day. Each such announcement is complete in itself. These announcements are separated by the notches 116 in the film and as the device is set for automatic operation the time device 90 will each 15 minutes set the machine into operation so that it will make an announcement of the time and such announcement could be accompanied by an advertising announcement such as that the time was being given by the courtesy of a watch company or the like.

After an announcement is made roller 96 grounds the circuit but the notches 116 being small the momentum of the drum 14 carries the notch past said roller so that when the machine actually stops the roller is again on a portion of the film and insulated from the drum. Other forms of announcements might be made as for example the device might be associated with the traffic signal and advise pedestrians to wait for the green light or the like. Additionally the film might have sets of notches or slots spaced vertically to control other devices, mechanical or otherwise, for example, fingers operated by or with the film slots may control the operation of display devices or the like.

Fig. 8 shows a modification of the switching means for bringing about stoppage of the machine following the making of an announcement or at other predetermined times. In such figure a bracket 120, which may replace the bracket 74a of Figs. 1 and 2 carries a normally open micro-switch 121 including an arm 122 pivoted at 123 and at its free end mounting a roller 124. This roller rides on the upper edge portion 125 of a film 126 trained about the drum 14 as above set forth.

A plunger 127 bears against the arm 122 and is normally held in such position thereby that contacts (not shown) of the micro-switch 121 are

in engagement and the switch 121 is closed. Film 126 in its upper edge 125 is provided at the desired spaced intervals with notches 128. As one of these notches moves or is carried under roller 124 the latter and the arm 122 may move downwardly permitting of a similar movement of plunger 127 whereby the contacts of switch 121 disengage to open a circuit.

This will result in the breaking of the circuit 10 of motor 15 and by momentum the notch 128 is carried beyond the roller 124 and the latter and arm 122 are again raised moving the plunger 127 upwardly closing switch 121. With the construction of Fig. 8 wherein the film is notched in its 15 edge portion provision is made for considerable movement of the switch roller 124 whereas with the construction first described the roller 96 has a movement only equal to the thickness of the film 31.

20 Referring now to Fig. 9 the lower portion of that figure which is marked off by the broken lines 129 shows the basic control system of the machine. Assuming that a suitable voltage has been applied to the terminals 131 and 132 and that the machine is at rest following an announcement the current flowing from terminal 131 flows through wire 133, terminal 134, wire 135, terminal 136, wire 137, a relay coil 138, a terminal 139, wire 140, terminal 141, the motor 15, wire 142, terminal 143 to terminal 132. It 25 will be noticed that the electric current has passed through a series circuit comprising a relay coil 138 which is of high resistance, and the motor 15 which is of comparatively low resistance.

30 From Ohm's law it will be seen that a greater voltage is developed across the component of greater resistance. Distributing the total voltage applied to the terminal 131 and 132 virtually the entire voltage applied will develop across the terminals 136 and 139 of the relay coil fully energizing the latter and that little voltage will be applied across the terminal 141 and 143 of the motor. The voltage applied across the motor terminals will be far below that necessary to produce the motor's rated torque. As a result 35 the armature 144 of the relay 138 will be held against the energized coil thus preventing a possible circuit through terminals 145 and 146 and the motor 15 will not function.

40 On momentary closing of a switch 147 the relay coil 138 is short circuited, then a low resistance path being offered to the electric current through the switch 147 the current no longer 45 flows through the relay coil to the motor but flows through said switch to the motor. Now the current flows from terminal 131 through wire 133, terminal 134, wire 148, switch 147, terminal 141, motor 15, wire 142, and terminal 143 to the terminal 132. As the relay coil 138 is no longer being energized a restoring spring 149 shifts the relay 50 armature 144 upwardly closing the switch 150 whereby a circuit is completed between the terminals 145 and 146. The voltage applied to the terminals 131 and 132 is now fully applied to the motor 15 causing the latter to develop its rated torque whereby it rotates the drum 14.

55 Since switch 150 is now closed it is noted that another path has been established providing a short circuit across the relay coil 138 and therefore opening of the switch 147 will not affect the 60 operation of the machine. This newly established short circuit is as follows: Starting at terminal 131, the electric current flows through wire 65 133, terminal 134, wire 135, terminal 136, a wire

151 to the micro-switch 121 which is being held closed, the wire 152, terminal 146, the switch 150, terminal 145, the wire 153, terminal 139, wire 140, terminal 141 and through the motor 15 and back to terminal 132. Just as long as this circuit is not interrupted the motor 15 will receive the full voltage applied to the terminals 131 and 132 although the switch 147 is open.

When one of the notches 128 in the upper edge of the film 126 moves under the roller 124 of the micro-switch 121 the arm 122 of that switch moves downwardly permitting plunger 127 a similar move and thereby breaking the contacts (not shown) within said switch. The short circuit that was established across the coil of the relay 138 by the path through the micro-switch 121 is momentarily broken. Instantly the current assumes a path from terminal 131 through wires 133 and 135 to terminal 136, then through the relay coil to the terminal 139 and through wire 149 to and through the motor to terminal 132.

As above set forth under these circumstances the greater part of the voltage applied to the terminals 131 and 132 is distributed across the terminals 136 and 139 fully energizing the relay coil. The armature 144 of the relay is therefore now shifted against the action of the spring 149 opening the switch 150 whereupon on the micro-switch 121 being again closed as the notch 128 moves from beneath the roller 124 there is no short circuit across the relay coil and the motor 15 having ceased to operate the machine is at rest.

The other circuits shown in Fig. 9 are concerned with the amplifier and an automatic time control means for bringing about a short circuiting of the relay coil 138 whereby to have the machine make an announcement each fifteen minutes. Thus referring further to said figure the amplifier is designated 154 and is connected with a speaker 155. At 156 is shown an electric clock motor driving cams 157 and 158 rotatable with the minute and second hands respectively (not shown) of said clock. Cam 157 has four cam faces 159 which successively engage and hold close, prior to the starting of an announcement and until such announcement is completed, a normally open switch 160. Cam 158 has a single cam surface 161 which once each minute engages and momentarily closes a normally open switch 162.

As the description proceeds it will become apparent that cams 157 and 158 may have other arrangements of cam surfaces and it will now be understood that the length of time during which the switches 160 and 161 are held closed depends on the length of the cam surfaces 159 and 161. The clock motor 156 is constantly operating and its current is from terminal 131, through wire 133, terminal 134, wire 163, the clock motor 156, and a return wire 164 to the terminal 132.

At a predetermined time as a minute or a fraction thereof before an announcement is made the cam surface 159 acts to close the switch 160 and thereby complete a circuit through the amplifier 154 to "warm up" the latter. Such circuit is completed from a connection 165 with the wire 163 through a wire 166 to wire 167, through the switch 160 to terminal 167a, wire 168, wire 169, and then through the amplifier and wire 170 to a connection 171 with the return wire 164. At a predetermined instance while the switch 160 is being held closed switch 162 is closed to bring about energizing of the motor whereby the latter operates the drum

14 to carry the film past the photo-electric cell to have the machine make an announcement.

The switch 162 is only momentarily closed and it is replacing the manually operable switch 147 previously described. When the switch 162 closes it short circuits the relay coil 138 so as to have the motor operate and the closing of switch 162 momentarily establishes a circuit as follows. From terminal 131 through wire 133, connection 134, wire 163, connection 165, wire 166, the switch 160, a wire 172, the switch 162, wire 173, a wire 174 connected with the terminal 145.

From there through wire 153 the circuit is completed to terminal 139 and through wire 140 to the motor terminal 141 and thence through the motor to 132. Instantly switch 162 is closed, the above circuit is established and the coil 138 deenergized. Thereupon the spring 149 acting on armature 134 closes the switch 150 establishing the circuit which is thereafter controlled by the micro-switch 121 as above set forth.

When the announcement has been made a notch 128 in the film permits of momentary opening of the micro-switch 121 so as to break the circuit about the coil 138 bringing about energization of the latter so that the switch 150 is opened and the coil remains energized so that the motor is no longer operating on the micro-switch being again closed when the notch 128 passes beyond the roller 124. In this connection it is to be understood that the momentum of the drum 14 and the other parts of the machine carries the notch beyond the roller.

When the four cam surfaces 159 are employed the machine will make an announcement at each interval of fifteen minutes although it will be understood that the number of cam surfaces may be varied depending on the number of announcements desired and as above suggested the entire machine may be manually controlled through the switch 147 provided means are employed to control the amplifier.

With the structure first described some difficulty is encountered in making an installation where the time device 30 must be synchronized with some other time device such as a clock on the wall or the like. With the circuit at Fig. 9 this difficulty is not encountered since but one timing device 156 would be employed and that would be the clock on display, as for example, mounted on a wall.

Referring to Fig. 10 the spindle 18 is continued upwardly from the disclosure first described and above the plate 19 supports a series of plates 19a, 19b, 19c and 19d, each supporting a hollow roll of film. Such rolls are designated 31, 31a, 31b, 31c and 31d respectively. In use the film moves from the center of a lower roll to the outside of the next upper roll and from the center of the top roll about the drum 14 and then to the outside of the lowermost roll 31.

With this arrangement a very long film may be used so that the device may operate over a period of hours. Any desired number of the additional plates and rolls of film may be used and suitable guide rollers 175 are provided. As the one motor drives all the stacked plates and film rolls there is little expense in adding the structure of Fig. 10 to that of Fig. 1 when the additional time is needed.

Having thus set forth the nature of my invention, what I claim is:

1. In an announcing apparatus, a drum, an endless film having a sound track, said film dis-

posed about said drum, a motor, a belt driven by said motor and trained over said drum and pressing the portion of the film disposed about the drum thereagainst whereby to rotate the latter and feed the film with the drum, and stationary means for translating the sound recorded in said sound track as the film is moved with the drum.

2. In an announcing apparatus, a drum, an endless film having a sound track, said film disposed about said drum, a motor, a belt driven by said motor and trained over said drum and pressing the portion of the film disposed about the drum thereagainst whereby to rotate the latter and feed the film with the drum, stationary means for translating the sound recorded in said sound track as the film is moved with the drum means for starting said apparatus at periodic time intervals, said film having notches therein, and means controlled by said notches for stopping said apparatus on movement of a notched portion of the film by a predetermined point.

3. In an announcing apparatus, a rotatable support, a rotatable drum, an endless hollow roll of film on said support, said film trained from the center of said roll over said drum and back to the outer side of the roll, means for rotating said support and thus said roll and for rotating said drum, said means for rotating the drum including a belt disposed about the drum on the portion of the film about the drum whereby to maintain the film against the drum and feed the film accurately with the drum, said film having a sound track, and translating means for reproducing the sound on said track as the film is moved with the drum.

4. In an announcing apparatus, a rotatable support, a rotatable drum, an endless hollow roll of film on said support, said film trained from the center of said roll over said drum and back to the outer side of the roll, means for rotating said support and thus said roll and for rotating said drum, said means for rotating the drum including a belt disposed about the drum on the portion of the film about the drum whereby to maintain the film against the drum and feed the film accurately with the drum, said film having a sound track, means for starting said apparatus at periodic intervals for the making of announcements, and means for automatically stopping said apparatus at the end of each announcement.

5. In an announcing apparatus, a rotatable support, a rotatable drum, an endless hollow roll of film on said support, said film trained from the center of said roll over said drum and back to the outer side of the roll, means for rotating said support and thus said roll and for rotating said drum, said means for rotating the drum including a belt disposed about the drum on the portion of the film about the drum whereby to feed the film accurately with the drum, said film having a sound track, said sound track comprising a plurality of complete announcements following one another, said film having a notch therein between each of said announcements, means for the starting of said apparatus at periodic intervals for the making of said announcements at predetermined times, and means controlled by said notches in the film for stopping said apparatus following each of said announcements, and translating means for reproducing the sound on said sound track as the film is moved with the drum.

6. In an announcing apparatus, a drum, an endless film having a sound track, said film dis-

posed about said drum, a motor, a belt driven by said motor and trained over said drum and engaging the portion of the film disposed about the drum whereby to rotate the latter and feed the film with the drum, said sound track comprising a plurality of complete announcements following one another, said film having a notch therein between each of said announcements, means for the starting of said apparatus at periodic intervals for the making of said announcements at predetermined times, and means controlled by said notches in the film for stopping said apparatus following each of said announcements, and translating means for reproducing the sound on said sound track as the film is moved with the drum.

7. In an announcing apparatus, a horizontally disposed drum, a film having a sound track, said film disposed about said drum, means including a driven belt holding the film against the drum and driving said drum and said film, means supporting a photo-electric cell at the inner side of said film, a light source at the outer side of said film, and a lens system aligned with said light source, sound track carrying portion of the film and said photo-electric cell.

8. In an announcing apparatus, a drum, an endless film having a sound track, said film disposed about said drum, a motor, a belt driven by said motor and trained over said drum and engaging the portion of the film disposed about the drum whereby to maintain the film against the drum and rotate the latter and feed the film with the drum, a photo-electric cell disposed at the inner side of said film, a light source at the outer side of said film, and a lens system aligned with said light source, film and photo-electric cell.

9. In an announcing apparatus, a drum, an endless film having a sound track, said film disposed about said drum, a motor, a belt driven by said motor and trained over said drum and engaging the portion of the film disposed about the drum whereby to rotate the latter and feed the film with the drum, said sound track comprising a plurality of complete announcements following one another, said film having a notch in its edge between each of said announcements, means for the starting of said apparatus at periodic intervals for the making of said announcements at predetermined times, and means riding on the edge of said film and controlled by said notches in the edge of the film for stopping said apparatus following each of said announcements, and translating means for reproducing the sound on said sound track as the film is moved with the drum.

10. In an announcing apparatus, a drum, an endless film having a sound track, said film disposed about said drum, a motor, a belt driven by said motor and trained over said drum and engaging the portion of the film disposed about the drum whereby to rotate the latter and feed the film with the drum, said film having notches therein, and means controlled by said notches.

11. In an announcing apparatus, a sound record having a notch therein, a translating means for reproducing sound from said record, an electric motor for moving said record by said translating means, a series circuit including said motor and a relay coil of greater resistance than said motor, a switch in said circuit and held in open position when said coil is energized, a switch in said circuit and normally maintained closed by said record but adapted to open on a notch reaching a predetermined position, another switch in

said circuit to momentarily short circuit said coil whereby to have said first switch close to maintain the coil short circuited and the motor operating on opening of the third switch, and said record controlled switch adapted on its opening to disturb said short circuit about the coil whereby the latter is again energized and opens the second switch.

12. In an announcing apparatus, a sound record having a notch therein, a translating means for reproducing sound from said record, an electric motor for moving said record by said translating means, a series circuit including said motor and a relay coil of greater resistance than said motor, a switch in said circuit and held in open position when said coil is energized, a switch in said circuit and normally maintained closed by said record but adapted to open on a notch reaching a predetermined position, another switch in said circuit to momentarily short circuit said coil whereby to have said first switch close to maintain the coil short circuited and the motor operating on opening of the third switch, and said record controlled switch adapted on its opening to disturb said short circuit about the coil whereby the latter is again energized and opens the second switch and a timing means for momentarily closing said third switch at predetermined intervals.

13. In an announcing apparatus, a rotatable support, a rotatable drum, an endless hollow roll of film resting on the upper side of said support, said support comprising a disc-like member slightly cone-shaped on its upper side whereby the film roll has a tendency to open and become loose and not bind, said film trained from the center of said roll over said drum and back to the outer side of said roll, means for rotating said support and thus said roll and for rotating said drum, said means for rotating the drum including a belt disposed about the drum on the portion of the film about the drum whereby to maintain the film against the drum and feed the film accurately with the drum, said film having a sound track, and translating means for reproducing the sound on said track as the film is fed about the drum.

14. In an announcing apparatus, a rotatable support, a rotatable drum, an endless roll of film on said support, said film trained from the center of said roll over said drum and back to the outer

side of the roll, means for rotating said support and thus said roll and for rotating said drum, said means for rotating the drum including a belt disposed about the drum on the portion of the film about the drum whereby to maintain the film against the drum and feed the film accurately with the drum, said film having a sound track, and translating means for reproducing the sound on said track as the film is fed about the drum.

15. In an announcing apparatus, a drum, an endless film having a sound track, said film disposed about said drum, means for rotating the drum and holding the film thereagainst and thus feeding the film, means for translating the sound recorded on the film as the latter is fed, means for starting said apparatus, said film having notches therein, and means controlled by said notches for stopping said apparatus on movement of a notched portion of the film by a predetermined point.

16. In an announcing apparatus, a rotatable support, a plurality of plates on said support and spaced vertically one above the other, a rotatable drum, an endless film including a hollow roll on each of said plates, said film trained from the center of each roll to the outer side of the next uppermost roll and from the center of the top roll over said drum and back to the outer side of the lowermost roll, means for rotating said support and thus said rolls and for rotating the drum, said means for rotating the drum including a belt disposed about the drum on the portion of the film about the drum whereby to feed the film accurately with the drum, said film having a sound track, and translating means for reproducing the sound on said track as the film is moved with the drum.

17. In an announcing apparatus, a sound film, a translating means including an amplifier, means for moving said film past the translating means for reproduction of the sound recorded on the film, cam means for closing a circuit to said amplifier, other cam means to thereafter in predetermined timed relation with said circuit closing cam means close a circuit to and place in operation the means for moving the film past the translating means, and other means thereafter operable on predetermined movement of said film to open both said circuits.

HAZARD E. REEVES.
